US00D967421S

(12) **United States Design Patent** (10) **Patent No.:** **US D967,421 S**
(45) **Date of Patent:** **** Oct. 18, 2022**

(54) **STAPLE CARTRIDGE**

(71) Applicant: **Ethicon LLC**, Guaynabo, PR (US)

(72) Inventors: **Frederick E. Shelton, IV**, Hillsboro, OH (US); **Jason L. Harris**, Lebanon, OH (US)

(73) Assignee: **Cilag GmbH International**, Zug (CH)

(**) Term: **15 Years**

(21) Appl. No.: **29/736,648**

(22) Filed: **Jun. 2, 2020**

(51) LOC (13) Cl. **24-02**

(52) U.S. Cl.

USPC **D24/145**

(58) **Field of Classification Search**

Primary Examiner — Lauren D McVey
Assistant Examiner — Justin A Johnson

(57) **CLAIM**

The ornamental design for a staple cartridge, as shown and described.

DESCRIPTION

FIG. 1 is a perspective view of a staple cartridge.
FIG. 2 is a top view of the staple cartridge of FIG. 1.
FIG. 3 is a bottom view of the staple cartridge of FIG. 1.
FIG. 4 is a right elevational view of the staple cartridge of FIG. 1.
FIG. 5 is left elevational view of the staple cartridge of FIG. 1.
FIG. 6 is a front elevational view of the staple cartridge of FIG. 1; and,
FIG. 7 is a rear elevational view of the staple cartridge of FIG. 1.
The broken lines in the drawings illustrate portions of the staple cartridge and form no part of the claimed design.

1 Claim, 4 Drawing Sheets
